SHOE CALK ASSEMBLY

John H. Shoemaker, Scappoose, Oreg.

Application February 23, 1952, Serial No. 273,110

2 Claims. (Cl. 36—59)

1

This invention relates in general to calks adapted to be mounted in the soles of boots or shoes, particularly in the boots of loggers, sportsmen, etc.

More specifically this invention relates to calked sole structure in which each calk is securely held in place in the outer sole of the boot or shoe through the intermediary of a steel eyelet which is first clinched into the outer sole, the eyelets being made of special annealed steel and of proper size to fit the lower ends of the calks perfectly, as hereinafter described.

Such eyelets comprise tubular metal members with a flanged bottom or outer end, the eyelets being driven through the leather or other material from which the outer sole of the shoe is made, and the inner ends of the eyelets then spread or deformed so as to clinch the eyelet securely in the sole. As is well known, an eyelet, when thus mounted, will generally remain firmly secured in the sole during the entire life of the sole.

Various methods have been employed for securing the shanks of calks in eyelets, for example, having a press fit between calk shank and eyelet or cutting threads on the inner cylindrical wall of the eyelet and providing corresponding threads on the shank of the calk. In general, however, I have found these methods to be unsatisfactory, either resulting in the calks working loose in the eyelets and being lost, or else involving too much labor and expense to be practical for the calking of boots and shoes for the ordinary trade.

An object of this invention is to provide an improved shoe calk assembly in which it will be practically impossible under ordinary circumstances for the inserted calk to become loose from its eyelet.

An additional object of the invention is to provide a shoe calk assembly of the type above indicated which can be manufactured inexpensively and will meet a popular demand.

A related object is to provide a shoe calk assembly which can be installed in place in a shoe sole without the employment of any means other than that now generally employed for installing ordinary calks, and an assembly in which the calk can be installed without requiring any additional labor or skill.

A more specific object of the invention is to provide an improved shoe calk assembly which will comprise eyelets made of inexpensive and unhardened metal and calks which may be of any specially hardened metal as desired.

2

These objects and incidental advantages I attain by making a calk of special construction and securing the same in a special manner in an eyelet, as hereinafter briefly described with reference to the accompanying drawings.

In the drawings:

Fig. 1 is an enlarged fragmentary section of a shoe sole showing an eyelet mounted in the customary manner in the sole, the section being taken longitudinally through the center line of the eyelet;

Fig. 2 is an elevation of my improved calk drawn to the same scale as the eyelet of Fig. 1;

Fig. 3 is a sectional elevation, drawn to the same scale as Figs. 1 and 2, showing the calk of Fig. 2 in the process of being forcibly inserted in place in the eyelet of Fig. 1;

Fig. 4 is a corresponding sectional elevation showing the calk entirely in place in the eyelet and in the shoe sole; and

Fig. 5 is a perspective view of a shoe sole illustrating the calks and eyelets set in place in a portion of the sole.

In Figs. 1, 3, 4 and 5 the reference character 10 indicates the outer or main sole of the boot B (Fig. 5). In heavy shoe and boot construction it is generally customary to have a midsole which is usually of somewhat less thickness than the outer sole, and such a midsole is indicated at 11 in Figs. 1 and 4. In such cases the calks are mounted in the outer sole.

In Fig. 1 an eyelet 12 of special type is shown secured in place in the usual manner in the sole 10. The eyelets are formed with a main tubular or cylindrical portion having an annular outwardly-extending flange 13 at one end. The opposite end of the eyelet at first will be either straight or, as is more customary, slightly bent inwardly to aid in the driving of the eyelet 14 through the sole or sole aperture. The eyeletting machines or other mechanism employed for driving such eyelets into place also spread the inner or top end into an outwardly-extending flange 14, or into a series of similar outwardly-extending prongs, which are then pressed down into the leather or sole material while the outer flange 13 is pressed inwardly, thus clinching the eyelet firmly in place. This is customary procedure and when the boot or shoe has a double sole, as indicated in Figs. 1 and 4, the eyelets will be secured in place in this manner generally before the sole is mounted. The secured eyelets 12 in the sole will have an internal diameter which is substantially uniform throughout except at the extreme outer and inner ends where the flanges 13 and

14 are formed. I use an eyelet with an internal diameter of .185 of an inch in the carrying out of my invention.

The calk of the invention is shown most clearly in Fig. 2. It comprises a lower tapered portion 21, which constitutes the spike portion or exposed portion of the calk when mounted, and an upper, slightly tapered portion 19 and 16. The upper portion constitutes the inserted or shank portion of the calk when mounted. The lower and upper portions, or the outer and inner portions, are separated by an annular shoulder or ridge 20 preferably formed with a pair of concave faces.

The lower, outer, or spike portion 21 of my improved calk terminates in a tip 22 which may be either conical as shown or more rounded if preferred. The upper, inner, or shank portion 19 and 16 of the calk is formed with a deep annular rounded groove 17, the wall of which forms a sharp shoulder 18 with the peripheral edge of the part 19. The taper of the two parts 19 and 16 is preferably the same. The upper or inner end of the calk terminates in a flattened conical surface 15, which is of no particular importance or significance beyond being a convenient way of finishing off this end of the calk in its manufacture.

In Fig. 2 I show, by way of illustration, the exact diametrical size of the calk shank at the points indicated, it being understood that the calk of this size is to be used with the special size eyelet previously mentioned, namely an eyelet having an internal diameter of .185 of an inch. Thus it will be noted that the diameter of the top or inner end of the calk corresponds to the original internal diameter of the eyelet and that the diameter of the shoulder edge 18 is .205 of an inch, or approximately .02 of an inch greater than the original internal diameter of the eyelet.

When the sole 10, with the eyelets mounted therein at the points desired, is ready for the calks, the calks are forced or driven into the respective eyelets as shown in Figs. 3 and 4. Inasmuch as the shank of the calk, except for the extreme top end, is of larger diameter than the internal original diameter of the eyelet, and since the metal of the eyelet is softer than the metal of the calk, deforming of the inside wall of the eyelet will occur as a result of the calk shank being forced into the eyelet. This deforming of the interior eyelet wall will cause some of the metal of the eyelet to be pressed up by the shoulder 18 and squeezed into the groove 17 with a result that when the calk has been forced into the final position shown in Fig. 4 a solid ring 23, integral with the eyelet wall, will fill the calk groove 17. I have found that no matter how rapidly the calk is forced into the eyelet this forming of a solid integral ring in the wall of the eyelet to correspond to the calk groove will take place provided the engaging parts are relatively substantially of the size indicated and relatively arranged as indicated. The result is that the inserted or shank portion end of the calk is not only held snugly and tightly and with a pressed fit in the eyelet, but the internal ring 23 in the eyelet also securely locks the calk to the eyelet. It will be evident that, with the calk anchored in this manner in the eyelet, as illustrated in Fig. 4, the calk can not drop out of the eyelet and can

not even work loose in the eyelet, and any external strain or stress sufficient to pull the calk from the eyelet, would result in pulling the eyelet from the sole. However, as is well known, the eyelet can not ordinarily be pulled from the sole unless the sole has deteriorated with use to the extent that it no longer provides proper anchorage for the eyelet, and under such condition the sole would at least require replacing.

Variations could be made in the exact shape as well as in the size of my improved calk without departing from the principle of my invention. Thus the taper or shape of the spike or exposed portion 22 could be varied, as well as its size, to suit different conditions of use for which the calked boots or shoes may be specifically designed, and it is not my intention to limit my invention otherwise than as set forth in the claims.

I claim:

1. A shoe calk assembly comprising a tubular eyelet anchored in the shoe sole, said eyelet having been originally formed with a substantially cylindrical inner wall, a calk having a spike portion and a tapered shank portion, an annular groove extending around said shank portion intermediate its ends, the intersection of the wall of said groove and the adjacent periphery of the larger diameter part of said shank portion forming a sharp shoulder, the diameter of the small end of said shank portion being substantially equal to the original diameter of said inner wall of said eyelet, said shank portion of said calk positioned in said eyelet and said inner wall of said eyelet deformed to correspond to the contour of said shank portion with part of said eyelet wall filling said groove of said shank, whereby causing said calk to be firmly held by said eyelet.

2. A shoe calk assembly comprising a tubular metal eyelet anchored in the shoe sole, an outwardly directed flange on said eyelet engaging the outer face of the sole, said eyelet having been originally formed with a substantially cylindrical inner wall, a calk of harder metal than said eyelet having a spike portion and a tapered shank portion, an annular rounded groove extending around said shank portion intermediate its ends, the intersection of the wall of said groove and the adjacent periphery of the larger diameter part of said shank portion forming a sharp shoulder, the diameter of the small end of said shank portion being substantially equal to the original diameter of said inner wall of said eyelet, said shank portion of said calk positioned in said eyelet and said inner wall of said eyelet deformed to correspond to the contour of said shank portion with part of said eyelet wall filling said groove of said shank, whereby causing said calk to be firmly held by said eyelet.

JOHN H. SHOEMAKER.
